UNITED STATES PATENT OFFICE.

JOHN SLOANE MEADE, OF BUFFALO, NEW YORK, ASSIGNOR OF ONE-HALF
TO WILLIAM COMERFORD, OF SAME PLACE.

DESIGN FOR A PORTABLE ELECTRIC-LAMP BODY.

SPECIFICATION forming part of Design No. 32,507, dated April 10, 1900.

Application filed February 27, 1900. Serial No. 6,687. Term of patent 14 years.

To all whom it may concern:

Be it known that I, JOHN SLOANE MEADE, a citizen of the United States, residing at Buffalo, Erie county, New York, have invented and produced a new and original Design for Portable Electric-Lamp Bodies, of which the following is a specification, reference being had to the accompanying drawings, forming a part thereof.

Figure 1 is an elevation of my invention. Fig. 2 is a perspective view of the same. Fig. 3 is a top end view. Fig. 4 is a butt-end view.

As shown in the drawings, the leading or material feature of my design consists of a cylindrical body A, which at its upper end is reduced conically, as shown at B, until it forms a neck C. From the neck C the outline takes the form of an ellipse, the major

axis being in parallel with the axis of the cylindrical body, as shown at D.

E is a cap which is flat, which fits over the butt-end, with a flange a.

F represents the lens or glass cover over the upper end, with a flange b.

Such design presents an ornamental and pleasing outline and design which is conformed to the several parts of the lamp.

Having described my invention, what I claim as new, and desire to secure by Letters Patent, is—

The design for a portable electric-lamp body as herein shown and described.

JOHN SLOANE MEADE.
